CLAMP FOR INTRAVENOUS FEEDING TUBES OR THE LIKE

Stephens N. Sato, San Diego, Calif., assignor, by mesne assignments, to Ivac Corporation, La Jolla, Calif., a corporation of California

Filed July 12, 1968, Ser. No. 12,727

Term of patent 14 years

Int. Cl. D8—02; D24—02
U.S. Cl. D54—13

FIGURE 1 is a front perspective view of a clamp for intravenous feeding tubes or the like embodying my new design;

FIGURE 2 is a rear elevational view of the clamp shown in FIGURE 1;

FIGURE 3 is a left side elevational view of the clamp shown in FIGURE 1;

FIGURE 4 is a front elevation thereof, the broken lines representing the feeding tube is shown for illustrative purposes only.

FIGURE 5 is a top plan view of the clamp shown in FIGURE 1.

I claim:

The ornamental design for a clamp for intravenous feeding tubes or the like, as shown and described.
